BURNS DICK, OF ST. LOUIS, MISSOURI, ASSIGNOR TO WAGNER ELECTRIC MANUFACTURING COMPANY, OF ST. LOUIS, MISSOURI, A CORPORATION OF MISSOURI.

RELAY.

1,312,522.

Specification of Letters Patent. Patented Aug. 12, 1919.

Application filed July 5, 1916. Serial No. 107,546

To all whom it may concern:

Be it known that I, BURNS DICK, a subject of the King of England, residing at the city of St. Louis, State of Missouri, United States of America, have invented a certain new and useful Relay, of which the following is such a full, clear, and exact description as will enable any one skilled in the art to which it appertains to make and use the same, reference being had to the accompanying drawings, forming part of this specification.

My invention relates to relays such as are used in connection with a storage battery and a dynamo electric machine adapted to charge the same. It is particularly applicable for use in connection with the battery and generator employed on automobiles. Some of the objects of my invention are, to produce a compact, cheap and mechanically well-protected relay, and to combine therewith an indicating device adapted to show whether the battery is connected to or disconnected from the charging generator. A further object is to produce a relay with light moving parts not likely to be displaced from any operating position by road shocks to which an automobile is subjected.

My invention will be better understood by reference to the accompanying drawings, in which Figure 1 is a longitudinal section through the relay and the indicating device; Fig. 2 is an end view of the relay from the terminal side; Fig. 3 an end view from the indicating side; Fig. 4 is a rear view of the indicating device; and Fig. 5 a diagram of connections.

The relay is contained in a cup-shaped receptacle 2, made of magnetic material provided with a metal but non-magnetic cap 30, through which protrude the two terminals 25 and 26. The cup 2 is fastened to a base 18 provided with a cover 19, shaped to form, with the base, a chamber for the reception of the indicating apparatus and adapted to be fastened to some convenient part of the automobile, for instance the cowl thereof. In the center of the cup 2 is placed a cylindrical core 3, held in firm and magnetic contact with the cup by means of the nut 17. Surrounding this core and located within the cup 2 are two concentrically arranged coils, 7 and 6. The coil 7 has fewer turns

than the coil 6 and is formed of larger wire. These coils are insulated from each other, 55 and are held in position by a block of insulating material 5, held in place by the pins 23. The connecting terminals 25 and 26 are attached to this insulating block, which also supports the contact terminal 16. 60

The metal bracket 24, clamped between parts of each of the terminals 25 and 26, in electrical connection with the terminal 25 but insulated from the terminal 26, supports, at the point 9, a flat spring 35 provided with 65 a contact 8 adapted to coöperate with the stationary contact 16 and normally held away from the latter. A plunger 10 of non-magnetic material fitting into an opening in the magnetic core 3 lined with a sleeve 22 of 70 non-magnetic material, carries the armature 4 of magnetic material and is loosely coupled by means of a rod and adjusting nut with the spring supporting the movable contact 8. The plunger is insulated from the spring 35 75 carrying the contact 8 by means of the bushing 27. The plunger 10 coöperates with a plunger 11, provided with a flange 12 and located in the axis of the core 3 within a hole smaller than that which accommodates 80 the plunger 10. The plunger 11 is preferably made of non-magnetic material. Its flange 12 coöperates with a projection 15 formed on the cross-piece 36 of the bracket 33 pivoted on the pin 14, which pin is held 85 in a support 20 attached to the base 18 of the relay. One side member of the support 20 is longer than the other and is bent back upon itself, as shown in Fig. 4 at 37, so as to form a stop coöperating with the cross-piece 36 of the bracket 33 for the purpose of limiting the travel of said bracket in one direction. The support 20 and the bracket 33 are preferably made of non-magnetic material. The bracket 33 carries a bent 95 plate 38, on which is inscribed the word "Off" at 31, and the word "Charge" at 13. The arrangement is such that one of the words comes opposite the window 32 provided in the cover 19, for one position of the 100 plunger, while the other word appears at this window for the other position of said plunger.

As more clearly shown in Fig. 4, the dynamo electric machine 28 may be provided with two main brushes and an auxil-

iary brush, the exciting winding 34 being connected between one main and the auxiliary brush. One of the main brushes is grounded, the other is connected to the terminal 26, which makes electrical connection with one end of each of the coils 6 and 7. The other end of the fine wire coil 6 is connected to the cup 2, which cup is grounded. The other end of the coil 7 is connected to the stationary contact 16 coöperating with the movable contact 8, which latter is in electrical connection with the terminal 25 to which is connected one pole of the battery 29, while its other pole is grounded.

15 The magnetic circuit of the relay comprises the core 3, the cup 2, and the movable armature 4 attached to the plunger 10. This movable armature has openings which permit the two terminals 25, 26, and the stationary contact 16 to project into the space inclosed by the cover 30, without interfering with the movement of the armature 4. The fine wire coil 6 is always in circuit with the main brushes of the dynamo 28, but the battery 29 is connected to said brushes only when the circuit is closed at the contacts 8 and 16, in which case the battery is connected to the dynamo through the winding 7.

20 This indicating relay should be mounted in a position in which its axis is not vertical in case gravity, rather than a spring, is relied upon to restore the indicator to its "off" position, and the projection 15 on the bracket 33 should lie below the center line of the relay.

25 The operation of this indicating relay, for any of the positions for which it is best suited, is as follows: As long as the dynamo 40 is at rest, or is running at such slow speed as to generate an E. M. F. smaller than the normal terminal voltage of the battery 29, the magnetization produced within the cup 2 by the fine wire coil 6 will not be sufficient to overcome the spring 35 and attract the armature 4 into close proximity with the edges of the cup 2. The contacts 8 and 16 will, therefore, be kept at a distance from each other, and the battery circuit, indicated 45 in Fig. 4, will be open. As long as the plunger 10 is under the control of the spring 35, the plunger 11, which may or may not be fastened to the plunger 10, will not exert any pressure on the projection 15 of the bracket 33, and the latter, impelled by gravity in this instance, will so place itself as to display, through the window 32 the word "Off" written on the plate 31. But as soon 50 as the voltage of the dynamo has reached a value approximating that of the storage battery 29, the armature 4 will be attracted and the battery circuit closed at the points 8 and 16. As long as the dynamo voltage is the same as that of the battery, no current will 55 flow either way, but as soon as the dynamo

voltage rises, a charging current will be sent into the battery, which charging current will circulate through the coil 7, energizing the magnetic circuit of the relay in the same direction as that in which it is energized by the coil 6, and therefore helping to keep the contacts 8 and 16 in close touch. The attraction of the armature 4 causes the plunger 10 to push the plunger 11 and its flange 12 against the projection 15 of the bracket 75 33, with the result that said bracket will be lifted, pivoting on the pin 14, to a position in which the plate 13, with the word "Charge" will come opposite the window 32, thus advising the driver of the automobile 80 that the battery is being charged. Should the speed of the dynamo fall to a value for which the voltage at the main brushes of the latter is less than the voltage at the terminals of the storage battery, then the 85 latter will send a current into the dynamo 28, with the result that the current through the coil 7 will be reversed, opposing the magnetization of the coil 6 and causing an immediate release of the armature 4. The 90 spring 35, now being in control, interrupts the battery circuit at the points 8 and 16, thus preventing the useless discharge of the battery 29. At the same time the pressure of the plunger 11 on the projection 15 is 95 relaxed and the bracket 33 falls into its position of rest, advising the driver of the change which has taken place, by displaying the word "Off."

Having fully described my invention, 100 what I claim as new and desire to secure by Letters Patent of the United States, is:

1. A relay comprising a cup, a core of magnetic material positioned in said cup, an exciting coil within said cup and surrounding said core, a block of insulating material held in position in one end of said cup, connecting terminals and a stationary contact terminal all supported on said block, and a movable contact member supported from a 105 connecting terminal and coöperating with the stationary contact terminal.

2. An indicating relay comprising a cylindrical cup of magnetic material, a core of magnetic material positioned in the cup, a 110 coil surrounding the core within the cup, and a circular disk of magnetic material movably supported adjacent to the end of the cup, said disk being of approximately the same diameter as the cup, and provided with 115 openings, and stationary connecting terminals for the relay extending through the openings in the disk.

3. In combination, a solenoid, an armature, a supporting base for said solenoid, a 120 cover provided with a sight-opening and forming with said base an inclosed chamber, an indicator in said chamber, and means whereby the armature may actuate the indicator.

4. In combination, a solenoid, an armature, a supporting base for said solenoid, a cover provided with a sight-opening and forming with said base an inclosed chamber, 5 an indicator in said chamber, and means whereby the armature may actuate the indicator, said means comprising an operating rod slidably mounted in the core of the solenoid.
- 10 5. In an indicating relay, the combination of a solenoid and armature therefor, an indicating device operated by the armature and provided with an indicating plate carrying different indications spaced apart thereon, a supporting base for the relay, and a cover for the indicating device attached to the base and provided with a sight-opening adjacent to the indicating plate.
- 15 6. In a relay, means forming a magnetic circuit, said means comprising a cylindrical outer member of magnetic material, a core of magnetic material centrally positioned within said outer member and in magnetic connection therewith at one end, an armature coöperating with said outer member and core, an exciting coil within the outer member and surrounding the central core, a block of insulating material for holding the coil in place, conducting terminals supported on said block, and a movable switch arm supported on said terminals.
- 20 7. In a relay, means forming a magnetic circuit, said means comprising a cylindrical outer member of magnetic material, a core of magnetic material centrally positioned within said outer member and in magnetic connection therewith at one end, an armature coöperating with said outer member and core, an exciting coil within the outer member and surrounding the central core, a block of insulating material for holding the coil in place, conducting terminals supported on said block, and a movable switch arm supported on said terminals.
- 25 8. In a relay, means forming a magnetic circuit, said means comprising a cylindrical outer member of magnetic material, a core of magnetic material centrally positioned within said outer member and in magnetic connection therewith at one end, an armature coöperating with said outer member and core, an exciting coil within the outer member and surrounding the central core, a block of insulating material for holding the coil in place, conducting terminals supported on said block, and a movable switch arm supported on the conducting terminals and coöperating with the contact terminal, said switch arm being in mechanical connection with the armature.
- 30 9. A relay comprising a cup, a core of magnetic material positioned in said cup and provided with a central opening, an exciting coil within said cup and surrounding said core, a block of insulating material held in position in one end of said cup, connecting terminals and a stationary contact terminal all supported on said block, a plunger slidingly mounted in the core and carrying an armature coöperating with said core, and a movable contact member coöperating with the stationary contact terminal and loosely coupled to said plunger.
- 35 In testimony whereof, I have hereunto set my hand and affixed my seal in the presence of the two subscribing witnesses.
